UNITED STATES PATENT OFFICE.

TERRENCE G. LOUIS, OF SPRINGFIELD, MASSACHUSETTS, ASSIGNOR TO WICO ELECTRIC COMPANY, A CORPORATION OF MASSACHUSETTS.

MAGNETO.

Application filed May 26, 1922. Serial No. 563,912.

To all whom it may concern:

Be it known that I, TERRENCE G. LOUIS, a citizen of the United States, residing at Springfield, in the county of Hampden and State of Massachusetts, have invented new and useful Improvements in Magnetos, of which the following is a specification.

This invention relates to magnetos and particularly to that class of magnetos, wherein an armature moves toward and away from and into and out of contact with magnetic poles.

Usually, in magnetos of this class, the armature moves toward and away from the poles along a line parallel with the axes of the cores and there results an impingement of the armature on the cores. This arrangement ordinarily results in a sharp noise due to the impingement and magnetos of this general class have generally been considered noisy in operation. While much has been done in recent years in the way of reducing the noise due to impingement and while there are magnetos of this class which are relatively quiet in operation, the movement of the armature in a direction parallel to the axes of the cores is an arrangement which tends to produce noise and will be very noisy unless special means are provided to counteract the inherent noise producing tendency.

In lieu of such means, this invention has for its object to move the armature into and out of engagement with its poles in a manner which is inherently quiet in operation.

More particularly, the invention has for an object to mount the armature for sliding movement in such a direction that those surfaces which are to contact with surfaces of the magnetic poles move parallel with the last-named surfaces and in such a manner that no movement in a direction normal to the pole surfaces can occur, whereby impingement, with the resultant noise, is prevented.

While the armature, according to the above object, may be actuated by any suitable mechanism, it is another object to provide mechanism for this purpose which is also inherently quiet in operation and which consists of a crank and link motion, producing harmonic motion of the armature.

In connection with the magneto, there is provided, in addition to the generating winding, a choking winding which is ar-

ranged in an electrical circuit capable of being opened and closed. This circuit is closed at a time before the armature has become separated from its poles and acts to hold the flux in the magnetic circuit until an appreciable separation of the armature and poles occurs, at which time it is opened to release the flux and cause a sudden change of flux in the magnetic circuit for the generation of current in the generating winding.

As a desirable feature, particularly useful where the armature moves continuously and where the contact between it and the poles progressively increases to a maximum and then decreases to zero, the choke winding circuit is arranged to be opened after initial and before maximum contact of the armature and poles to permit the flux to build up rapidly in the magnetic circuit and is again closed during the time of decreasing contact and before separation of the armature and poles to hold the flux as above described.

A further object of the invention is to provide in a magneto, of the general type defined, generally improved mechanical structure.

Other objects and advantages will appear in the following description and in the illustrative embodiment of the invention in the accompanying drawings, in which,

Fig. 1 is a front elevational view of a magneto embodying the invention;

Fig. 2 is a sectional plan view taken on the line 2—2 of Fig. 1;

Fig. 3 is a bottom plan view thereof;

Fig. 4 is a fragmentary cross-sectional view taken on the line 4—4 of Fig. 1;

Fig. 5 is a diagrammatical view, illustrative of the magnetic circuit and electrical circuits of the magneto; and

Figs. 6 and 7 are fragmentary small scale elevational views, taken at right angles to each other, and illustrating the manner of driving the magneto from an engine.

Referring to these drawings: the magneto comprises, in general, a suitable source of magnetic flux, cores or pole pieces therefor, an armature movable toward and away and into and out of contact with said cores to periodically connect and disconnect them and form a magnetic circuit from said source of alternately low and high reluctance, a generating winding associated with the

cores, a choking winding also associated therewith, interrupter mechanism to open and close an electrical circuit including the choking winding, a frame to support the elements described, mechanism for operating the armature, and mechanism for operating the interrupter mechanism.

- The source of magnetic flux may be of any suitable type, but usually, and by preference, consists of a series of permanent bar magnets 10. In this instance four such magnets are superposed one upon another in vertically stacked relation with the like poles of each arranged at the same end. The ends of all the magnets of the series are received in substantially U-shaped clips 11 of magnetic material and tightly fit, or are made to tightly fit, the upper and lower parallel interior surfaces of the U-shaped recesses of these clips, whereby a good magnetic connection between the clips and magnets is obtained as well as an adequate mechanical connection to hold the magnets against displacement in the clips.
- The cores, following preferred practice, are laminated and are shown at 12, each core, as shown, having substantially the shape of a square prism. Both cores are mounted in spaced parallel relation and each is magnetically connected at its upper end to the adjacent clip 11 in the following manner. The upper end of each core 12 is received in mating half square recesses in two blocks 13 and 14 of magnetic material. A screw 15 passes through each block 13 and the core 12 and is threaded into block 14, thereby clamping the laminations together and insuring a good magnetic connection between the core and blocks. These blocks are supported from the frame 16 of the magneto, in rectangularly outstanding relation thereon, by the screws 15, described, which as shown in Fig. 2 pass through frame 16 before entering block 13. The front faces of the blocks 14 are tied together by a bar 17 which mechanically, but not magnetically, connects these blocks and is secured thereto, as by screws 18. The upper face of each pair of blocks 13 and 14, supports a clip 11 which is secured thereto, as by screws 19. The lower ends of the cores 12 are clamped together in a similar manner except that, instead of two sets of clamping members, a single set, comprising members 21 and 22, are used. These members are of non-magnetic material and mechanically, but not magnetically connect, the cores. The screws 23, by means of which members 21 and 22 are clamped together, also serve to hold these members to frame 16.
- To complete a magnetic circuit from source 10, the lower ends of cores 12 (which constitute magnetic poles) are engaged and connected by an armature 24, which as indicated in Figs. 3 and 4 is of laminated construction.

This armature is movable toward and away from the cores 12 to magnetically connect and disconnect them and vary the reluctance of the magnetic circuit. In the present case, the armature is mounted for sliding movement in a direction at right angles to the longitudinal axes of cores 12, and, as viewed in Fig. 3, is movable from the illustrated position to the right, a distance sufficient to uncover the left hand core 12 and leave an appreciable air gap between the left hand end of the armature and the nearest portion of such core. The armature has a portion at each end, substantially coextensive in area with the core ends, which is adapted to abut the latter, and the intermediate portion of the armature lies in a lower plane. Consequently, when the armature is moved to the position just described, the right hand core is also magnetically disconnected from the armature and the intermediate portion of the armature is separated by the vertical air gap between it and such core. The armature is slidable, and has bearing surfaces to engage bearing surfaces on the lower face of the joined members 21 and 22, with which the lower ends of cores 12 are flush and it is movable between two gibs 25, which are suitably secured, as indicated to these members. The armature may be supported by resting upon two rolls 26 which are mounted on studs 27 secured in lugs 28 on one of the gibs 25, or may be otherwise supported in any suitable manner.

The generating winding and the choke winding are preferably applied to each core 12 and between the members 17 and 21. As shown, the choking winding comprises two coils 30, one on each core, which coils are suitably connected, as in series, by a wire 31 (Fig. 5). The generating winding comprises two coils 32, applied over the coils 30, and these coils 32 are suitably connected, as in series, by a wire 33. One terminal of each winding is usually grounded to the frame of the magneto, as indicated at 34 and 35 in Fig. 5. The other terminal of the generating winding is the service terminal and is indicated at 36 as connected to a spark plug 3. The other terminal of the choking winding is connected, as by a wire 37, to one of two relatively movable breaker points 38 and 39, of which the latter will be assumed to be movable and the former stationary. The movable point 39 is, as will appear, in contact at all times with the frame of the magneto and is thus grounded, as indicated at 40 in Fig. 5. Following preferred practice, a condenser 41 is bridged across the breaker points in the usual manner.

The breaker points 38 and 39 form the essential elements of the interrupter mechanism above alluded to, which will now be

described in full detail. The stationary breaker point 38 is fixed to and insulated from the cap of a hollow tubular casing 43 and the movable point 39 is slidably mounted therein and fixed to a rod 44 which extends downwardly and loosely through a washer 45 and an operating lever 46. The washer 45 is fixed in the illustrated position by being received in a suitable recess in one of gibs 25, as shown in Fig. 4, and, between this washer and a shoulder 47 on rod 44, a spring 48 is interposed which tends to force point 39 into abutment with point 38. The rod 44 is threaded at its lower end and carries an adjustable abutment 49, in the nature of a nut, which may be held in adjusted position by a lock nut 50. The abutment 49 is adapted to be engaged, at proper times, by lever 46 and moved to separate the points 38 and 39 against the tension of spring 48.

The interrupter operating mechanism consists of a member mounted for movement in a direction substantially at right angles to the line of travel of the armature. As shown, this member takes the form of a lever 46 which is virtually pivoted at one end to the member 21. A screw 51 passes loosely through one end of lever 46 and is threaded into member 21. A spring 52 encircles screw 51 and is interposed between member 21 and the upper face of lever 46, thus holding the opposite face of the latter against the head of screw 51. The above construction is merely illustrative of one of many ways of mounting this lever and any other suitable way may be used as desired. The other end of lever 46 is provided with two longitudinally spaced and oppositely directed inclined cam surfaces 53 and 54, which are adapted to be engaged by a pin 55 projecting laterally from armature 24 to move the lever 46 downwardly and, by reason of abutment 49, cause the opening of the breaker points 38 and 39.

According to some features of this invention, the armature may be moved in the path described by any suitable means, whether such means are quick acting or not. The present means are of a crank motion character and are preferred by reason of their quietness in operation although they are not necessarily essential so far as all features of the invention are concerned. Such means are shown in Figs. 6 and 7, and produce an approximately harmonic motion of the armature which gives a gradual stop and start at the ends of the stroke and thus contributes to the desired result of quiet operation. The particular way in which this motion is obtained from the engine will vary largely according to the conditions encountered and is not particularly material. However, as an illustrative example of one suitable manner of mounting the magneto on, and driv-

ing it from, an internal combustion engine, the structure shown in Figs. 6 and 7 is given. The magneto itself, represented conventionally by M, is stationarily mounted in any suitable way on the frame of an engine A. 70 On the cam shaft c of the engine, an eccentric e is fixed, which, by means of the strap r, oscillates a rocker arm a and the latter is connected by links l and m to the pin 55 and armature 24. 75

In operation, the armature 24 reciprocates continuously in proper timed relation with the engine and does not remain in full and complete contact with the poles of the magnetic circuit except for an instant. Neither 80 does the armature move out of engagement with its poles at any greater speed than it moves into engagement with them. With these conditions, the choking winding and interrupter mechanism are essential for success for the flux must be permitted to build up rapidly in the magnetic circuit owing to relatively short duration of contact between the armature and poles. 85 This flux must also be held in the magnetic circuit until the relatively slow moving armature has created a sufficient air gap in the magnetic circuit to permit a rapid change of flux therein when released.

With this type of magneto, a current may be generated on either or both movements of the armature and the latter condition has been illustrated. Thus, when the armature is in the illustrated position, wherein there is full and complete contact between it and the poles, the breaker points 38 and 39 are separated because, as the armature neared such position, the pin 55 engaged the cam 53 and operated lever 46. Thus, the choking winding, which has previously been in a closed circuit to retard a building up of flux in cores 12, is open circuited to permit the flux to build up rapidly in the magnetic circuit and create a sudden change of flux 95 for the generation of current in coils 32. As 100

the armature moves to the right and before it has become separated from cores 12, the pin 55 rides off lever 46 and the latter is allowed to rise and the breaker points allowed to close under the influence of spring 48. 115 The choking winding is now in a closed circuit to hold the flux for an interval and retard the relatively gradual change of flux which would otherwise occur. Continued 120 movement of the armature to the right causes complete separation of the armature and cores and the establishment of an air gap therebetween and, at such time, pin 55 engages cam 54 and causes the breaker points 125 to again open to suddenly release the flux and cause the desired substantial change of flux for the generation of current in coils 32. As the armature moves to the left and before again engaging the cores, pin 55 rides off cam 54 and the breaker points close to 130

retard the gradual increase in flux which would otherwise occur and prevent any substantial change of flux until the armature has been moved into contact with the poles, as above described.

The invention is characterized by a sliding movement of the armature along a plane substantially at right angles to the axes of the cores, as distinguished from a similar movement along these axes, which movement results in an impingement of the armature on the cores and more or less of a blow. While the force of this blow can be diminished to avoid, or at least greatly reduce, the resulting noise, the arrangement is one which tends to the production of noise and the present invention seeks to provide a different arrangement which is not inherently noisy. By sliding the armature at right angles to the axes of the cores and providing an adjacent surface, on which the armature may slide and which prevents relative vertical movement between the armature and cores, the possibility of an impingement is eliminated. As an added element, which is desirable although not indispensable to the result of quiet operation, the crank motion operating means for the armature is provided, since this motion also contributes to the desired result.

The invention has been disclosed herein, in an embodiment at present preferred, for illustrative purposes, but the scope of the invention is defined by the appended claims rather than by the foregoing description.

What I claim is:

1. In a magneto, a source of magnetic flux, a member of magnetic material connected with each pole of said source, a generating winding associated with at least one of said members, an armature mounted to slide across said members and contact at the same time with each to complete a magnetic circuit from said source through said winding and movable to a position wherein it is out of contact with each member at the same time, said members being spaced one from the other along the path of movement of said armature.

2. In a magneto, having two magnetic pole pieces adapted to be periodically and magnetically connected and disconnected, an armature reciprocable in a plane at right angles to the longitudinal axes of the pole pieces and movable into and out of contact therewith, and means for guiding the armature into contact with the pole pieces without relative impingement thereof.

3. In a magneto, a source of magnetic flux, a member of magnetic material connected with each pole of said source, a generating winding associated with at least one of said members, a slidable armature adapted to contact at the same time with each member to complete a magnetic circuit from

said source through said winding and movable to a position wherein it is out of contact with each member at the same time, said members being spaced one from the other along the path of movement of said armature and disposed both on the same side of said armature.

4. In a magneto, a source of magnetic flux, a member of magnetic material connected with each pole of said source, a generating winding associated with at least one of said members, an armature mounted to slide laterally with respect to said members and supported so that it is free to be drawn in a direction normal to said sliding movement into close contact with said members under the influence of magnetic attraction, said armature adapted to contact at the same time with each member to complete a magnetic circuit from said source through said winding and movable to a position wherein it is out of contact with each member at the same time, said members being spaced one from the other along the path of movement of said armature and disposed at right angles to the path of movement of the armature.

5. In a magneto, having two magnetic pole surfaces adapted to be periodically and magnetically connected and disconnected, an armature provided with surfaces to contact with the first-named surfaces and mounted for reciprocable movement into and out of contact therewith in a direction substantially parallel to the planes of said surfaces and also for free movement in a direction normal to said surfaces under the influence of magnetic attraction into close contact therewith, and means having bearing surfaces for the armature and adapted to guide it into contact with the pole surfaces without relative impingement thereof.

6. In a magneto, a source of magnetic flux, a member of magnetic material connected with each pole of said source, a generating winding associated with at least one of said members, a slidable armature adapted to contact at the same time with each member to complete a magnetic circuit from said source through said winding and movable to a position wherein it is out of contact with each member at the same time, said members being spaced one from the other along the path of movement of said armature and disposed both on the same side of said armature and at right angles to the path of movement thereof.

7. In a magneto, a source of magnetic flux, a member of magnetic material connected with each pole of said source, a generating winding associated with at least one of said members, a slidable armature having two spaced portions of magnetic material to contact with said members at the same time and including a connecting portion of

- 5 magnetic material so disposed as to be incapable of contacting with said members at any position of the armature, whereby in one position of the armature a magnetic circuit of low reluctance from said source through said members and winding is formed and at another position of the armature the reluctance of said circuit is greatly increased, said members being spaced one 60 from the other along the path of movement of said armature and disposed both on the same side of said armature.
8. In a magneto, a source of magnetic flux, two cores extending in parallel relation 15 away from said source and connected at one end thereto, one to each pole thereof, a generating winding on each core, an armature adapted when in one position to contact with the other end of each core and connect the cores, said armature being recessed 20 between its core contacting portions, and means for sliding the armature from said position to another position in a direction at right angles to the axes of said cores to move the armature out of engagement with said cores and bring the recessed portion opposite one of said cores.
9. In a magneto, a slidable armature, two 25 magnetic pole surfaces adapted to be periodically connected together by said armature and subsequently disconnected, means for reciprocating the armature in a plane substantially parallel with said surfaces, and means for guiding the armature into contact 30 with both surfaces at the same time, said means allowing the armature to be drawn into close contact with the said surfaces by the magnetic attraction therefrom.
10. In a magneto, of the type wherein an 35 armature moves into and out of contact with magnetic poles to vary the reluctance of a magnetic circuit and a generating winding is associated with said circuit in which currents are induced by the variation of flux 40 therein, a choke winding associated with said circuit and arranged in an electrical circuit which can be opened and closed, means for moving the armature so that the area of contact between it and the poles 45 progressively increases from zero to a maximum and then decreases to zero again, and means for closing said electrical circuit prior to contact between the armature and poles and for opening it during the time of 50 progressive increase of contact.
11. In a magneto, of the type wherein an 55 armature moves into and out of contact with magnetic poles to vary the reluctance of a magnetic circuit and a generating winding is associated with said circuit in which currents are induced by the variation of flux 60 therein, a choke winding associated with said circuit and arranged in an electrical circuit which can be opened and closed, means for moving the armature so that the 65 area of contact between it and the poles progressively increases from zero to a maximum and then decreases to zero again, and means for closing said electrical circuit prior to contact between the armature and poles and for opening it during the time of progressive increase of contact.
12. In a magneto, of the type wherein an 70 armature moves into and out of contact with magnetic poles to vary the reluctance of a magnetic circuit and a generating winding is associated with said circuit in which currents are induced by the variation of flux 75 therein, a choke winding associated with said circuit and arranged in an electrical circuit which can be opened and closed, means for imparting continuous reciprocating motion to the armature and in such direction that the contact of the armature with its poles progressively increases in area to a maximum and then immediately commences to decrease and progressively decreases to zero, and means for closing said 80 electrical circuit prior to contact between the armature and poles and for opening it during the time of progressive increase of contact.
13. In a magneto, having a source of magnetic flux, primary and secondary windings 85 associated therewith and an armature slideable into and out of contact with the magnetic poles of said source and interrupter mechanism including relatively fixed and 90 movable breaker points included in circuit with said primary winding to open and close the same, a cam member disposed adjacent the path of travel of the armature and mounted for movement at substantially right 95 angles thereto, a reciprocating cam follower movable back and forth with the armature for engaging and moving said member, and operating connections between said member and the movable breaker point of the interrupter mechanism.
14. In a magneto, having a source of magnetic flux, primary and secondary windings 100 associated therewith and an armature reciprocable into out of contact with the magnetic poles of said source and an interrupter mechanism which includes relatively fixed and movable breaker points with means 105 yieldingly holding them in engagement, an electrical circuit including said primary winding and breaker points a member disposed adjacent the path of travel of the armature and mounted for movement at substantially right angles thereto, a cam surface provided on said member, means 110 movable with the armature for engaging said surface and moving said member when the armature approaches the end of one stroke of its reciprocable movement, and operating connections between said member 115
15. In a magneto, having a source of magnetic flux, primary and secondary windings 120 associated therewith and an armature reciprocable into out of contact with the magnetic poles of said source and an interrupter mechanism which includes relatively fixed and movable breaker points with means 125 yieldingly holding them in engagement, an electrical circuit including said primary winding and breaker points a member disposed adjacent the path of travel of the armature and mounted for movement at substantially right angles thereto, a cam surface provided on said member, means movable with the armature for engaging said surface and moving said member when the armature approaches the end of one stroke of its reciprocable movement, and operating connections between said member 130

and the movable breaker point to separate said points when the member is moved.

15. In a magneto, having a source of magnetic flux, primary and secondary windings associated therewith and an armature reciprocable into and out of contact with the magnetic poles of said source and an interrupter mechanism which includes relatively fixed and movable breaker points with means 10 yieldingly holding them in engagement, an electrical circuit including said primary winding and breaker points a member disposed adjacent the path of travel of the armature and mounted for movement at 15 substantially right angles thereto, a cam surface provided on said member, means movable with the armature for engaging said surface and moving said member when the armature approaches each end of its 20 stroke, and operating connections between said member and the movable breaker point to separate said points when the member is moved.

16. In a magneto, having a source of magnetic flux, primary and secondary windings associated therewith and an armature 25 slideable into and out of contact with the magnetic poles of said source and interrupter mechanism including relatively fixed and 30 movable breaker points included in circuit with said primary winding to open and close the same, a cam member disposed adjacent the path of travel of the armature and mounted for movement at substantially 35 right angles thereto in a direction toward and away from said poles, means movable

back and forth with the armature for engaging and moving said member, operating connections between said member and the movable breaker point of the interrupter 40 mechanism, and yieldable means for holding said breaker points in engagement and for holding said member in its normal position.

17. In a magneto of the type wherein an armature is movable into and out of contact with magnetic poles, means for moving the armature progressively into and out of contact with its poles, so that the area of contact therebetween gradually increases 50 from zero to a maximum and then decreases to zero again.

18. In a magneto, of the type wherein an armature moves into and out of contact with magnetic poles to vary the reluctance of a magnetic circuit and a generating winding is associated with said circuit in which currents are induced by the variation of flux therein, a choke winding associated with 60 said circuit and arranged in an electrical circuit which can be opened and closed, means for moving the armature so that the area of contact between it and the poles progressively increases from zero to a maximum and then decreases to zero again, and 65 means for closing said electrical circuit prior to disengagement of the armature and poles and for opening it after such disengagement has occurred.

In testimony whereof I have affixed my 70 signature.

TERRENCE G. LOUIS.
